[57] CLAIM

The ornamental design for an oval soap bar, as shown and described.

DESCRIPTION

FIG. 1 is a perspective view of an oval soap bar showing my new design;

FIG. 2 is an enlarged front elevational view thereof; FIG. 3 is an enlarged side elevational view thereof, the opposite side being identical in that the design is symmetrical;

FIG. 4 is an enlarged rear elevational view thereof;

FIG. 5 is an enlarged end elevational view thereof, both the right and left ends being identical.
